[57] CLAIM

The ornamental design for a paperboard pallet, as shown and described.

DESCRIPTION

FIG. 1 is a front perspective view of a first embodiment of a paperboard pallet embodying my new design;

FIG. 2 is a top plan view thereof;

FIG. 3 is a bottom plan view thereof;

FIG. 4 is a front elevational view thereof, a rear elevational view being identical thereto; and

FIG. 5 is a side elevational view thereof, the other side elevational view being identical thereto;

FIG. 6 is a top plan view of a second embodiment of a paperboard pallet embodying my new design;

FIG. 7 is a bottom plan view thereof; and

FIG. 8 is a side elevational view thereof, the other side being identical thereto, and the front and rear elevational views being illustrated in FIG. 4;

FIG. 9 is a top plan view of a third embodiment of a paperboard pallet embodying my new design;

FIG. 10 is a bottom plan view thereof; and

FIG. 11 is a side elevational view thereof, the other side being identical thereto, and the front and rear elevational views thereof being illustrated in FIG. 4;

FIG. 12 is a top plan view of a fourth embodiment of a paperboard pallet embodying my new design;

FIG. 13 is a bottom plan view thereof; and

FIG. 14 is a side elevational view thereof, the other side being identical thereto, and the front and rear elevational views thereof being illustrated in FIG. 4;

FIG. 15 is a top plan view of a fifth embodiment of a paperboard pallet embodying my new design;

FIG. 16 is a bottom plan view thereof; and,

FIG. 17 is a side elevational view thereof, the other side being identical thereto, and the front and rear elevational views thereof being illustrated in FIG. 4.
